WASHING STATION

Camillus M. Rohyans, Indianapolis, Ind., and
Charles G. Brown, Williamsport, Pa.

Application April 29, 1933, Serial No. 668,478

3 Claims. (Cl. 299—84)

This invention relates to washing stations, and more particularly to apparatus for cleaning locomotives or other large objects, in which apparatus the cleansing medium comprises a mixture of different kinds of fluids.

Heretofore, for washing locomotives, it has been proposed to employ a spray nozzle to which flexible hose carrying fluids of different nature are connected, the fluids being mixed together within the spray nozzle. With such apparatus each hose is made long enough to reach from an outlet of the supply mains to either end of the locomotive to be cleaned. Due to the length of hose required and the bulky nature of the spray nozzle, such apparatus is difficult to move about and fatiguing to operate.

One object of our invention is to provide more simple, yet equally efficient, apparatus overcoming the above recited difficulties as to handling by the operator. To this end our invention is characterized by supply mains which are connected together at spaced intervals along the side of the object to be cleaned to afford a series of discharge points at which the fluids are mixed, each of which discharge points is adapted for connection with a single short length hose leading to a spray nozzle of light and simple construction.

Another object of the invention is to provide at the discharge outlets of such apparatus means for combining a cleansing liquid with compressed air in such manner as to cause the jet issuing from the spray nozzle to have a spasmodic, rather than a continuous action, with very short time intervals between pressure surges, the action being similar in effect to that of a rapidly operated machine gun.

Other more specific objects and advantages characterizing our invention will become more fully apparent from the description hereinafter set forth of one embodiment or example of the practice of the invention, having reference to the accompanying drawings. Of the drawings:

Fig. I represents a side elevation of the complete apparatus comprising the washing station.

Fig. II represents a plan view of a section of track at the washing station, showing the arrangement of the supply lines and the position of their discharge outlets with relation to the track.

Fig. III represents an enlarged detailed view, partly in cross section of one discharge outlet.

Fig. IV represents an enlarged detailed view of the spray nozzle.

Fig. V represents a perspective view of a loco-

motive at the washing station showing the spray nozzle in operation.

Fig. VI represents an enlarged view, partly in cross section, of the connection at which oil and hot water are combined, the location of this connection being indicated by the circle VI in Fig. I.

Fig. VII is an enlarged sectional view of the end portion of the spray nozzle; and,

Fig. VIII is an end view of the tip of the spray nozzle.

With reference initially to Fig. I of the drawings, the apparatus there shown comprises equipment including heating apparatus housed within a building designated at 1 and additional equipment located adjacent to a railway track 2.

The equipment housed within the building 1 includes in the illustrated example of our invention a water heater 3, an oil tank 4 and a hand pump 5. Water enters the heater 3 through a pipe 6 and there surrounds and is heated by a steam radiator 7. From the heater 3 water passes through a pipe 8 to a T-connection 9 where it is mixed with oil from the tank 4, and from thence the combined water and oil passes out of the building 1 through a pipe 10 constituting the supply for the cleansing liquid and leading to the washing platform adjacent to the track 2. A portion of the water from the heater 3 passes through a pipe 11 to the bottom of the oil tank 4, thus serving to equalize the pressure in the oil tank with that in the water heater.

Oil is admitted to the oil tank 4 by means of the hand pump 5. From the oil tank 4 it passes through a pipe 12 to the T-connection 9 where it mixes with the water from the heater 3. In Fig. VI the T-connection 9 is shown in detail, and it will be observed that by means of a cylindrical filler 13 disposed within the pipe 12 and having a restricted opening 14 therethrough the proportion of oil to water is regulated to the desired amount. Suitable drains 15, 16, 17 are provided for the water heater 3, oil tank 4 and steam radiator 7, respectively.

From any convenient source of supply, not shown in the drawings, a pressure medium such as compressed air is also lead to the washing platform, the compressed air supply line being designated at 20. At the washing platform the supply lines 10, 20 carrying the mixture of oil and water and carrying compressed air, respectively, are arranged in parallel relation with each other alongside the track 2. By means of branch lines 10a, 20a, crossing over beneath the track 2, the supply lines 10, 20 are extended to each side of the washing platform, as shown clearly in Fig. II. At

spaced intervals along the fluid supply lines 10, 20 discharge outlets are provided to afford means to which the spray nozzles may be quickly connected and disconnected, the points at which the discharge outlets are placed being designated by the letters A to F, inclusive.

To support the fluid supply lines 10, 20 as well as to guard them against injury, we preferably provide a series of upright posts 21 and railings 22 10 at each side of the track 2. While in the illustrated example of our invention three discharge outlets are provided at each side of the washing platform, it will be apparent that, according to the size of the object to be washed, the number 15 of outlets and the distance between them may be varied.

One discharge outlet is shown in detail in Fig. III. Within the compressed air lines 20, at each discharge outlet, there is a T-connection 23 to 20 which is applied a nipple 24 and a cut-out valve 25. In the oil and water supply line 10 there is provided a pipe cross 26 at a point adjacent to each T-connection 23 of the air supply line 20. A tubular extension 27 from each cut-out valve 25 extends upward through the side arms of the pipe cross 26 closing the lower arm and passing through the upper arm without closing it. To the pipe cross 26 there is attached an adjusting nut 28 through which the oil and water passes. 30 To the adjusting nut 28 there is applied a fitting in the form of a pipe reducer 29 which affords a restricted opening surrounding the end of the tubular extension 27. To the pipe reducer 29 there is applied a casing in the form of a nipple 30 which serves as the mixing chamber within which the cleansing liquid, oil and water, is mixed with compressed air from the air line 20. It will be observed that the discharge connection from the air supply line 20 which comprises the nipple 24, the valve 25 and the tubular extension 27, is relatively small in diameter, whereas the discharge connection from the oil and water supply line 10, which comprises the pipe cross 26, the adjusting nut 28, the pipe reducer 29 and the nipple 30, is relatively large in diameter. By having the large discharge connection from the liquid supply line 10 terminate in a reduced end, surrounding the relatively small discharge connection from the air supply line 20, the oil and water is entrained in the jet of air issuing from the tubular extension 27, and is caused to be expelled at a high velocity.

Moreover, the pipe reducer 29, which has a gradually diminishing cross sectional area toward the upper end, serves as a choke causing the cleansing medium to issue in a spasmodic or interrupted jet. The effect resulting from the use of the above described apparatus is that successive pressure surges rapidly follow one upon another, not unlike a machine gun, and this action produces a very effective jet for cleaning the surfaces of a locomotive, especially the regions thereof where dirt or grease is lodged in nooks and corners and is difficult to remove by a continuous stream.

The particular relation of the tubular extension 27 within the pipe reducer 29 necessary to effect the above described spasmodic jet action will vary according to the pressures employed in the supply lines 10, 20 and may be determined by trial and error, the adjustment of this relation being obtained by turning the adjusting nut 28 in one direction or the other.

Beyond the nipple 30 a cut-out valve 31 is applied, and to the top of this valve there is affixed

a fitting preferably in the form of a universal coupling including a socket member 32. All of the elements thus far described comprise permanent and stationary parts of the washing platform, whereas the spray nozzles to be hereinafter described are of a portable nature.

To the coupling 32, which is in the form of a socket, a plug 33 at the end of the spray nozzle is adapted to be applied. The complete spray nozzle is most clearly illustrated in Fig. IV. It comprises generally a flexible hose 34, a barrel 35, and a short length pipe 36 at the end of the barrel. By means of suitable wire clamps 37, the flexible hose is attached at one end to the plug 33 and at the other end to the barrel 35. On the barrel 35 a hand grip 38 is provided, and adjacent to this hand grip there is a globe valve 39. A portion of the barrel 35 is covered with tubular insulation 40, which affords a convenient grip for the operator.

The pipe 36 is preferably inclined at an angle from the barrel 35, and as shown in Fig. VII, the pipe 36 terminates in a cone spray tip 41 held in place by a cap 42. As shown in Fig. VIII, the cone shaped tip 41 has therein a series of perforations 43 and is so designed as to cause concentrated jets to issue therefrom.

The operation of the apparatus herein described will be apparent from the description of the constituent elements thereof. As illustrated in Fig. V, the spray nozzle is particularly adapted for the washing of locomotives and is conveniently handled by a single operator. In washing a locomotive, it is desirable to have one operator working at each side thereof. It will be especially noted that the spray nozzle is of simple and light construction, and that it carries with it only a short length of hose 34. The operator applies this hose to one discharge outlet such as that represented at D, performs the cleaning operation on one end of the locomotive; and when that portion of the locomotive is completed he detaches the flexible hose 34 from the discharge outlet D, and applies the same to the discharge outlet E, and continues the cleaning operation on the central portion of the locomotive. Subsequently the spray nozzle is disconnected from the discharge outlet E and connected to the discharge outlet F, so that the operator may wash the remaining end of the locomotive and thus complete the washing of one side. At the opposite side of the locomotive a similar operation is performed, either concurrently or after the washing of the first side has been completed.

It will also be particularly noted that each discharge outlet includes two valves, one valve 31 controlling the fluid passing through the spray nozzle, and the other valve 25 controlling the compressed air used. These valves 31, 25 are within convenient reach of the operator. Thus the arrangement described makes possible the easy handling of the spray nozzle and of the hose connected to it, and eliminates the difficulties experienced with heavy spray nozzles carrying several relatively long hoses.

While we have described one preferred arrangement of the supply lines and discharge outlets found to be convenient for the purpose of washing locomotives, it will be readily appreciated that various changes in the form and arrangement of the parts are contemplated, such changes being within the spirit of our invention as defined in the annexed claims.

Having thus described our invention, we claim:

1. Apparatus for applying a cleansing medium

80

comprising supply lines, one for carrying a cleansing liquid and another for carrying a pressure medium, said liquid supply line having a discharge connection therein in the form of a pipe cross, and said pressure line having a discharge connection therein in the form of a pipe T, an extension leading from the side arm of said pipe T through the side arms of said pipe cross, said extension closing the first such arm 5 of said pipe cross and passing through the second arm without closing it, a casing connected to said latter arm and disposed at the end of said extension, said casing forming a mixing chamber whereat said cleansing liquid and pressure medium are combined, and spray means connected to said casing. 10 15

2. Apparatus for applying a cleansing medium comprising supply lines, one for carrying a cleansing liquid and another for carrying a pressure medium, said liquid supply line having a discharge connection therein in the form of a pipe cross, and said pressure line having a discharge connection therein in the form of a pipe T, an extension leading from the side arm of said 20 25 pipe T through the side arms of said pipe cross, said extension closing the first such arm of said pipe cross and passing through the second arm

without closing it, a pipe fitting connected to said latter arm and surrounding said extension, said fitting diminishing in cross sectional area toward the end of said extension and terminating in a casing forming a mixing chamber whereat said cleansing liquid and pressure medium are combined, and spray means connected to said casing. 80

3. Apparatus for applying a cleansing medium comprising parallel supply lines, one for carrying a cleansing liquid and another for carrying a pressure medium, said liquid supply line having discharge connections in the form of pipe crosses at intervals therealong, and said pressure line having discharge connections in the form of pipe T's at corresponding intervals therealong, an extension leading from each said pipe T through the side arms of the adjacent pipe cross of the liquid supply line, said extension closing the first such arm of said pipe cross and passing through the second arm without closing it, a casing connected to said latter arm and disposed at the end of said extension, said casing forming a mixing chamber whereat said cleansing liquid and pressure medium are combined, and spray means connected to said casing. 85 90 95
